Primary Examiner — Manpreet S Matharu*Assistant Examiner* — Yolanda Robinson(74) *Attorney, Agent, or Firm* — Manatt, Phelps & Phillips LLP(57) **CLAIM**

The ornamental design for a snap-on cover for striker, as shown and described.

DESCRIPTION

FIG. 1 is a top perspective view of a snap-on cover for striker;

FIG. 2 is a top plan view thereof;

FIG. 3 is a left side view thereof;

FIG. 4 is a right side view thereof;

FIG. 5 is a top end view thereof;

FIG. 6 is a bottom end view thereof;

FIG. 7 is a top perspective view of a second embodiment;

FIG. 8 is a top plan view thereof;

FIG. 9 is a left side view thereof;

FIG. 10 is a right side view thereof;

FIG. 11 is a top end view thereof; and,

FIG. 12 is a bottom end view thereof.

The broken lines shown in the snap-on cover for striker are for portions that form no part of the claimed design.
